(57) **CLAIM**

The ornamental design of a vehicle brake, as shown and described.

DESCRIPTION

FIG. 1 is a perspective view of a vehicle brake in accordance with our design as viewed from the rear left;

FIG. 2 is a perspective view of the vehicle brake of FIG. 1 as viewed from the rear right;

FIG. 3 is a left side elevational view of the vehicle brake shown in FIGS. 1 and 2;

FIG. 4 is a right side elevational view thereof;

FIG. 5 is a rear elevational view thereof;

FIG. 6 is a front elevation view thereof;

FIG. 7 is a top plan view thereof; and,

FIG. 8 is a bottom plan view thereof.
